CASE CARRIER

Roy D. Shockey, Trenton, Mo.

Application September 30, 1939, Serial No. 297,374

1 Claim. (Cl. 294—15)

This invention appertains to new and useful improvements in article handling means and more particularly to a carrier especially adapted for carrying beverage cases.

The principal object of the present invention is to provide a quickly attachable and removable handle structure for beverage cases which in use will employ several bottles of a filled case as a fulcrum or abutment point for promoting the proper bearing of the case when being carried by the device.

These and other objects and advantages of the invention will become apparent to the reader of the following specification.

15 In the drawings:

Figure 1 represents a fragmentary longitudinal sectional view through a beverage case and the carrier device.

Figure 2 represents a fragmentary top plan view showing a beverage case with the carrier attached.

Figure 3 is a top plan view of the carrier.

Figure 4 is a front elevational view of the carrier.

25 Figure 5 is an enlarged detailed sectional view on the line 6—6 of Figure 4.

Figure 6 is a side elevational view of the carrier.

In the drawings, wherein like numerals designate like parts, it can be seen in Figure 1 that numeral 5 generally refers to a beverage case, which includes the bottom wall 6, side walls 7, end wall 8 slotted as at 9, and the cell-defining partitions 10. In the partitions 10 are disposed the bottles 11 containing beverage.

35 Numeral 12 generally refers to the carrier which consists of the substantially heart-shaped hook frame 13, the pointed portion of the frame 13 being open and having depending leg portions 14—14 which terminate in backwardly disposed

40 lugs 15—15, these legs 14 and 15 defining hooks for engagement through the slot 9 of an end wall 8.

The back portion 16 is adapted to brace the car-

rier against the neck portions of several bottles 11, as clearly suggested in Figures 1 and 2.

The handle frame 17 is of inverted U-shape, the lower portions of the handle frame 17 being welded or otherwise secured as at 18 to the hook frame 13 at the end portions of the back portion 16.

Obviously, when the frame 13 is disposed over the neck portions of several bottles and the hooks 14—15 disposed through a slot 9, the case can be 10 lifted by lifting on the handle frame 17 and the fulcrumed disposition of the back portion 16 against the bottles 11 will serve to set the case in a proper inclined position so that bottles will not fall out of the case while the case is being 15 carried.

Furthermore, the use of this implement 12 serves to permit the person carrying the case to have the case farther away from his legs so that the case will not be continuously rubbing against 20 one of his legs while he is engaged in carrying the same.

While the foregoing specification sets forth the invention in specific terms, it is to be understood that numerous changes in the shape, size 25 and materials may be resorted to without departing from the spirit and scope of the invention as claimed hereinafter.

Having described the invention, what is claimed as new is—

A carrier for bottle cases of the type having hand slots in the ends thereof comprising a substantially U-shaped frame having laterally and backwardly bent end portion defining hooks, said hooks being adapted to be disposed through a 35 hand slot in one end of a bottle case, the bight portion of the U-shaped frame being adapted to embrace the neck portions of one or more bottles in the case adjacent the hand slot, and a U-shaped handle having the ends of its leg portions 40 secured to the U-shaped frame adjacent the bight portion thereof, said handle being disposed substantially at right angles to the said frame.

ROY D. SHOCKEY.
